ATTORNEYS.

UNITED STATES PATENT OFFICE.

JOHN F. LONERGAN, OF ST. LOUIS, MISSOURI.

COOPER'S BEVEL.

SPECIFICATION forming part of Letters Patent No. 270,086, dated January 2, 1883.

Application filed September 1, 1882. (Model.)

To all whom it may concern:

Be it known that I, JOHN F. LONERGAN, of St. Louis and State of Missouri, have invented a new and Improved Cooper's Bevel, of which 5 the following is a full, clear, and exact description.

My invention relates to bevels used by coopers in the manufacture of tubs and tanks for jointing the staves.

10 The object of the invention is to furnish an instrument by which the angles necessary in a great variety of sizes may be obtained, so as to avoid the necessity of a separate instrument for each size of tub or tank.

15 The invention consists in an adjustable bevel constructed as hereinafter described and claimed.

Reference is to be had to the accompanying drawings, forming a part of this specification, in 20 which similar letters of reference indicate corresponding parts in all the figures.

Figure 1 is a side elevation of my improved beveling-instrument. Fig. 2 is a detail section at the joint of the arm. Fig. 3 shows the instrument fitted for use as a try-square.

The instrument consists of two blades, A and B, which may be of wood or metal, preferably the latter, the blade A being what I term the "base" of the instrument, and the blade B 30 the "adjustable arm." The base A is formed with two parallel and longitudinal slots, *a*, at one of its ends, and the arm B is made with two similar slots, *b*. The arm is attached by screws *c*, passing through the slots, and held 35 by clamping-nuts *d*. This construction is to allow of the adjustment of the arm upon the base at right angles or in any position in the length of the slots as may be desired.

As a guide for the adjustment of the arm B, 40 the base A is marked with cross-lines *e*. The angles of these lines to the side of the base varies, each one being for a different size tub or tank—from two feet to ten feet, more or less—so that when the arm is placed upon either of 45 these lines its angle to the base corresponds

to the angle required for joining the staves in that size of tank. The lines are numbered for both the diameter and circumference for each size.

In beveling the staves the operator works 50 from the diameter. The circumference sizes are applied for commerce in estimating the quantity of material required for the tank. The inside edge of the base A is curved or beveled as shown, so that the bevel may be applied 55 directly to the outside edge of the stave in case the stave should be rough or warped. This prevents the bevel from rocking on the stave, and secures uniformity of the bevel in the length of the stave.

The use of this instrument secures uniformity and accuracy in the joining of staves for tubs and tanks. It may also be used as a try-square by setting the arm B at right angles to the back or straight edge of the base, as shown 65 in Fig. 3, and used as a carpenter's bevel. The bevels are to be made in three sizes—the first size for tubs from two to ten feet in diameter, the second from ten to twenty feet, and the 70 third from twenty to thirty feet.

Having thus described my invention, I claim as new and desire to secure by Letters Patent—
1. The cooper's bevel consisting of the L-shaped instrument, with its leg or base A provided with parallel longitudinal slots *a* and 75 graduations *e*, and its foot or arm B provided with parallel longitudinal slots *b* and set-screws *d*, said arm or foot being capable of adjustment at different angles to the leg or base A, as shown and described, and for the 80 purpose set forth.

2. The combination of the base A, formed with slots *a*, the slotted arm B, and clamping-screws, substantially as shown and described, for use in the manner specified.

JOHN F. LONERGAN.
